W. H. F. JESKA,

WINDOW CATCH.

APPLICATION FILED AUG. 18, 1921.

1,425,593.

Patented Aug. 15, 1922.

Inventor:
William H. F. Jeska,
by: John E. Dryden
his Attorney.

UNITED STATES PATENT OFFICE.

WILLIAM H. F. JESKA, OF ST. PAUL, MINNESOTA.

WINDOW CATCH.

1,425,593.

Specification of Letters Patent. Patented Aug. 15, 1922.

Application filed August 18, 1921. Serial No. 493,203.

To all whom it may concern:

Be it known that I, WILLIAM H. F. JESKA, a citizen of the United States, residing at St. Paul, in the county of Ramsey and State 5 of Minnesota, have invented new and useful Improvements in Window Catches, of which the following is a specification.

It is my object to provide a novel and efficient window catch which is designed to 10 securely fasten both sashes of a window in any desired position.

A further object of my invention is to provide simple and inexpensive means for locking windows in partially open position.

Another object of my invention is to provide a device of this kind which is adapted to be quickly and easily mounted on any common type of window having vertically 15 sliding sashes.

Other objects of my invention will appear and be more fully pointed out in the following specification and claims.

Referring to the drawings, which illustrate the best form of my device at present 20 known to me, Figure 1 is a perspective view of my improved window catch mounted on a window of common type; Fig. 2 is a plan view of the same, adjacent portions of the upper sash, guide strips and rope being 25 shown in section; Fig. 3 is a section taken on the line 3—3 of Fig. 2 and Fig. 4 is a section taken on the line 4—4 of Fig. 2.

The base plate 10 of my device is adapted to be secured to the upper surface of the 30 lower sash 11 by means of screws 12 and a pair of upwardly projecting ears 13, integral with the base 10, form a support for one end of an arm 14 on the other end of which is mounted a head 15. This head 15 35 is slotted at 16 to receive the arm 14, and a rivet 17, passing through said head and the end of said arm, pivotally joins said head and arm. Two abutments 18 and 19 are formed on the extremity of the head 15 40 to engage the vertical surfaces, respectively, of the window frame 20 and guide strips 21, these abutments being separated to allow clearance for the window weight 45 rope 22.

The upper sash 23 is adapted to be engaged by a wedge 24 which is slidable on an inclined projection 25 formed on the head 15. A screw 26, which is rigidly held in the wedge 24, is slidable substantially 50 vertically in a slot 27 in the projection 25 to fasten the wedge 24 to the head 15 and

allows limited vertical movement of said wedge. A pair of circular depressions 28 are formed in opposite faces of the wedge 24 to facilitate raising said wedge as hereinafter described and rubber shoes 29 and 30, mounted, respectively, on the vertical surfaces of the abutment 18 and wedge 24, are provided to engage the adjacent surfaces of the window frame 20 and upper 55 sash 23.

The lower end of the arm 14 is pivotally supported between the ears 13 by means of a rivet 31, and notches 32, in the upper edges of said ears, are adapted to be engaged by a latch 33 which is pivotally mounted on the upper surface of the arm 14 by means of a rivet 34.

Operation.

75

In use the base plate 10 is secured to the upper surface of the lower sash 11, by means of the screws 12, far enough away from the vertical surface of the window frame 20 so that the arm 14 is supported in inclined position by the shoe 29 in engagement with the surface 20. When in this position the abutment 19 bears against the outer surface of the guide 21 and the shoe 30, on the wedge 24, bears against the adjacent surface of the upper sash 23. When the arm 14 is in the inclined position the latch 33 is turned to engage the notches 32. Now if an attempt is made to raise the lower sash the cantilever action of the arm 14 will thrust the shoe 29 firmly against the frame 20 so that upward movement of said sash is prevented and if an attempt is made to lower the upper sash 23 the shoe 30, on the wedge 24, will draw said wedge downward, forcing the abutment 19 against the guide strip 21 and preventing downward movement of the latter sash. The latch 33 is provided to prevent a person outside of the building from disengaging my catch from the window frame by reaching in with a curved stick or the like. To disengage the wedge 24 from the upper sash it is only necessary to pull said wedge upward by grasping the depressions 28, and to make the whole catch inoperative the latch 33 is turned free of the notches 32 and the arm 14 carrying the head 15 is tilted backward to the position indicated in dotted lines in Fig. 4. It will be readily understood that when my catch is in the locked position (the full line position in the drawings) either or both sashes may be left par-

tially open and firmly secured against further opening by persons outside the building. My device is thus especially applicable to buildings in which it is desired to leave the windows open for ventilation without danger of burglary.

Having described my invention what I claim as new and desire to protect by Letters Patent is:

- 10 1. In a catch for a window having vertically slideable sashes and guide strips for said sashes, a plate adapted to be secured to the upper surface of the lower sash, an arm tiltably supported at one end on said plate, a head mounted on the free end of said arm whereby said arm is held in inclined position, abutments formed on said head to severally engage the window frame and outer edge of a guide strip and means 15 mounted on said head for engaging the upper sash.
- 20 2. In a catch for a window having vertically slideable sashes and guide strips for said sashes, a plate adapted to be secured to the upper surface of the lower sash, an arm tiltably supported at one end on said plate, a head pivotally supported on the free end of said arm whereby said arm is held in inclined position, abutments formed on said head to severally engage the window frame and outer edge of a guide strip, a wedge arranged on 25 said head to engage the upper sash and a latch mounted on said arm to prevent movement of said abutments from engagement with said window frame, and guide strip.
- 30

and outer edge of a guide strip and a wedge arranged on said head to engage the upper sash.

3. In a window catch, a plate adapted to be secured to the upper surface of a window sash, upwardly projecting ears formed on said plate, an inclined arm tiltably supported at its lower end between said ears, a head arranged on the upper end of said arm to engage the window frame and a wedge 35 mounted on said head and formed to engage the upper sash.

4. In a catch for a window having vertically slideable sashes and guide strips for said sashes, a plate adapted to be secured to the upper surface of the lower sash, ears on said plate, an arm tiltably supported at one end between said ears, a head pivotally supported on the free end of said arm whereby said arm is held in inclined position, abutments formed on said head to severally engage the window frame and outer edge of a guide strip, a wedge arranged on 45 said head to engage the upper sash and a latch mounted on said arm to prevent movement of said abutments from engagement with said window frame, and guide strip.

In testimony whereof, I have hereunto signed my name to this specification.

WILLIAM H. F. JESKA.
